UNITED STATES PATENT OFFICE

2,638,155

CUSHION SPRING STRUCTURE

William A. Clark, Detroit, Mich.

Application May 31, 1951, Serial No. 229,165

10 Claims. (Cl. 155—181)

1

This invention relates to improvements in cushion spring structure.

The main objects of this invention are:

First, to provide a cushion spring structure which is well adapted for use in a front seat cushion providing an effective springable upholstery support and at the same time providing foot room or a space under the rear portion of the cushion.

Second, to provide a structure embodying these advantages in which the upholstery is effectively supported throughout.

Third, to provide a structure having these advantages which may be very economically produced.

Objects relating to details and economies of the invention will appear from the description to follow. The invention is pointed out in the claims.

A preferred embodiment of the invention is illustrated in the accompanying drawings, in which:

Fig. 1 is a fragmentary plan view of a cushion structure embodying my invention, certain parts being conventionally shown and only such parts being illustrated as are deemed necessary to disclose a practical embodiment of my invention.

Fig. 2 is a fragmentary end elevational view partially in section from front to rear of the cushion.

Fig. 3 is an enlarged fragmentary plan view of certain of the parts.

Fig. 4 is a fragmentary perspective view illustrating certain of the details of the upholstery supporting strip.

Fig. 5 is a fragmentary plan view of the modified form or embodiment of my invention.

In the accompanying drawing I have illustrated only such parts of a commercial spring structure as seems to be desirable in disclosing my invention and enabling the practical embodiment thereof. Certain of the parts are conventionally shown and certain parts are shown as having a flock surface coating, this being that disclosed in my pending application, Serial No. 212,412, filed February 23, 1951. This coating is illustrated as it is a desirable feature in the embodiment illustrated, not only as to the spring structure generally but as to the upholstery supporting strip disposed at the rear of the body springs as will be described in detail.

The embodiment of my invention illustrated comprises a base designated generally by the numeral 1 and including a spring member or members on which the helically coiled body springs 2

are mounted. The springs are desirably mounted on a panel indicated at 3 in Fig. 1, the mounting being disclosed in my said application.

The base is provided with upwardly and rearwardly extending arms 4 on which the rear rail 5 is mounted. This rear rail is in the preferred embodiment formed of angle iron facing forwardly and downwardly. The details of attaching the rear rail to the supporting arms 4 are not illustrated. The base, spring supports, rear rail and its supporting arms constitute a supporting frame.

The top coils of the coiled body springs 2 are connected by cross helical tie members 6. The upholstery designated generally by the numeral 7 is supported by the springs and the helical tie members. The helical tie members provide yielding springable connections for the adjacent body springs. This type of spring connection is old in the art but it is especially desirable in connection with the other features to be pointed out.

To provide a foot space beneath the rear portion of the upholstery, the rear body springs 2 are substantially spaced forwardly relative to the rear rail 5 which is in approximately the plane of the tops thereof. To support the upholstery at the rear of the rear body springs, I provide an upholstery supporting strip designated generally by the numeral 8. This, in the embodiment shown in Figs. 1 to 4 inclusive, comprises an extensibly springable helically coiled front member 9 and a rear member 10 which is relatively nonextensible and desirably formed of a wire core strand 11 having a covering 12 thereon of twisted paper. These front and rear members are connected by transversely spaced parallel metal strips 13, the ends 14 of which are clamped around the front and rear members or clampingly embrace the same, thereby holding the members 13 in their spaced parallel relation.

This upholstery supporting strip is positioned at the rear of the body springs and constitutes an upholstery supporting extension of the body springs. The upholstery supporting strip is connected by means of clips 15 which secure the member 9 to the top coils of the adjacent body springs. It is connected by means of the helically coiled extension springs 16 to the rear rail 5, the springs 16 being provided with hooks 17 engaging the rear member 12 and with hooks 18 engaging holes 19 provided therefor in the rear rail 5. The front member yields extensibly when pressure is applied to the body springs to which it is connected and this compression yielding is also furthered by the springable connections 16

for the upholstery supporting strip to the rear rail. The result is that the upholstery is effectively supported and at the same time foot space is provided beneath the rear portion of the cushion. This is particularly desirable in some automobile structures in which the front and rear seats are quite closely spaced in order to permit the positioning of the rear seat forwardly relative to the rear axle.

The upholstery cover designated by the numeral 28 is drawn around the rear rail and secured to the upholstery securing rod 21 disposed below the rear rail and connected thereto by the hangers 22, the upholstery securing means being indicated at 23. After the spring assembly, including the upholstery supporting strip, has been completed, it is dipped in an adhesive and flock, indicated at 24, applied thereto with the result that all of the parts are given a soft mat-like covering. The adhesive, as pointed out in my aforesaid pending application, enters the joints of the parts and prevents noise such as commonly results from the movement of one part of a spring assembly on another or any noise such as results from the coils of the springs coming into contact. This is particularly desirable where the cushion is open at the rear as there is nothing to effectively prevent the escape of sound although in some embodiments a curtain is disposed at the rear of the body springs.

In the embodiment of my invention shown in Fig. 5, the upholstery supporting strip is designated generally by the numeral 25. The front longitudinal member 26 is the same as the rear longitudinal member 27 which is like the member 10 of Figs. 1 to 4. The transverse strips 13 are the same as in the previously described embodiment. In this embodiment the upholstery supporting strip is connected to the body springs 2 by means of the helical tie wire 28 which is spiralled around the member 26 with certain of its coils engaging the top coils of the adjacent body springs. The members 26 and 27 of the upholstery supporting strip of this embodiment are nonextensible but they are flexible and yield or bend with the deflecting of the body springs. The upholstery supporting strip is connected to the rear rail 29 which in this embodiment is in the form of a rod by means of the extension springs 46.

The structure of Fig. 5 is somewhat more economical than that of the other embodiment in that the front member 26 is formed of the paper covered wire strand as distinguished from the helically coiled front member 9; however, there are substantial advantages in the great flexibility and extensibility of the helically coiled member 9. The helical tie 28 may be engaged with the parts connected thereby by mechanical rotation thereof while the clips 15 are individually and manually applied.

I have illustrated and described my invention in a highly practical embodiment thereof. I have not attempted to illustrate certain other embodiments or adaptations as it is believed that this disclosure will enable those skilled in the art to embody or adapt my invention as may be desired.

Having thus described my invention, what I claim as new and desire to secure by Letters Patent is:

1. In a spring structure, the combination of a base, upright helically coiled body springs carried by said base, resilient ties for the top coils of said springs, a rear rail carried by said base and disposed in rearwardly spaced relation to the body

springs, an upholstery supporting strip disposed between the body springs and rail and comprising a helically coiled springably extensible front member, a nonextensible rear member, spaced connecting members clampingly engaging said front and rear members, clips securing the front member to the top coils of adjacent body springs, and spaced helically coiled extension spring connecting the rear member to said rear rail.

2. In a spring structure, the combination of a base, body springs carried thereby, a rear rail carried by said base and disposed in rearwardly spaced relation to the body springs, an upholstery supporting strip disposed between the body springs and rail and comprising a helically coiled springably extensible front member, a rear member, spaced members connecting said front and rear members, the front members being secured to the adjacent body springs, and spaced helically coiled extension springs connecting the rear member to said rear rail.

3. In a spring structure, the combination of a base, body springs carried thereby, a rear rail carried by said base and disposed in rearwardly spaced relation to the body springs, an upholstery supporting strip disposed between the body springs and rail and comprising spaced flexible front and rear members, spaced members connecting said front and rear members, the front member being secured to the adjacent body springs, and springable means connecting the rear member to said rear rail.

4. A spring structure comprising a supporting frame and body springs carried thereby, said frame including a rear rail disposed in elevated rearwardly spaced relation to the body springs, and an upholstery supporting strip disposed between the body springs and rail and comprising a resilient front member and a relatively non-resilient nonextensible rear member and connecting upholstery supporting means, the front member being secured to the adjacent body springs and the rear member being resiliently connected to the rear rail.

5. A spring structure comprising a supporting frame and body springs carried thereby, said frame including a rear rail disposed in rearwardly spaced relation to the body springs, an upholstery supporting strip disposed between the body springs and rail and comprising a springably extensible front member and a relatively non-extensible rear member, and spaced parallel members connecting said front and rear members, the front member being secured to the top coils of adjacent body springs and the rear member being springably connected to the said rear rail.

6. A spring structure comprising a supporting frame and body springs carried thereby, said frame including a rear rail disposed in rearwardly spaced relation to the body springs, an upholstery supporting strip disposed between the body springs and rail and comprising a springably extensible front member and a relatively nonextensible rear member, and upholstery supporting means carried by said front and rear members, the front member being secured to the top coils of adjacent body springs and the rear member being springably connected to the said rear rail.

7. A spring structure comprising a supporting frame and helically coiled body springs carried thereby, said frame including a rear rail disposed in rearwardly spaced relation relative to the top coils of the body springs, an upholstery

supporting strip disposed between said body springs and rail and comprising nonextensible front and rear members, upholstery supporting means extending between said front and rear members, the front member being connected to the top coils of adjacent body springs, and spring means connecting the rear member to said rear rail.

8. A spring structure comprising a supporting frame and body springs carried thereby, said frame including a rear rail disposed in rearwardly spaced relation to the body springs, an upholstery supporting strip disposed between the body springs and rail and comprising front and rear members, spaced parallel connecting members disposed with their ends clampingly embracing said members, a helically coiled tie member spiralled upon the front member with coils thereof embracing coils of the adjacent body springs, and extension springs connecting the rear member of said upholstery strip to said rear rail.

9. A spring structure comprising a supporting frame and body springs carried thereby, said frame including a rear rail disposed in rear- 25

wardly spaced relation to the springs, an upholstery supporting strip disposed between said body springs and rail and comprising front and rear members, upholstery supporting means carried by said front member, a helically coiled tie member disposed with coils thereof embracing said front member and with certain of the coils engaging the body springs, and springably yielding connections for the rear member to said rear rail.

10. A spring structure comprising a supporting frame and body springs carried thereby, said frame including a rear rail disposed in rearwardly spaced relation to the springs, an upholstery supporting strip disposed between said body springs and rail and comprising flexible front and rear members, upholstery supporting connections for said members, the front member being connected to adjacent body springs, and spring connections for the rear member to said rear rail.
